UNITED STATES PATENT OFFICE.

LOUIS STEINBERGER, OF NEW YORK, N. Y.

HIGH-POTENTIAL STRAIN-INSULATOR.

No. 927,186.

Specification of Letters Patent.

Patented July 6, 1909.

Application filed July 30, 1906. Serial No. 328,342.

To all whom it may concern:

Be it known that I, LOUIS STEINBERGER, a citizen of the United States, and a resident of the city of New York, borough of Brooklyn, in the county of Kings and State of New York, have invented a new and Improved High-Potential Strain-Insulator, of which the following is a full, clear, and exact description.

10 My invention relates to strain insulators used in connection with electrical conductors, and more particularly to conductors adapted to convey currents of high potential.

15 Among the several purposes of my invention are the following: 1, to give the various parts of the strain insulator such conformity as will confer upon them a comparatively high degree of mechanical strength coupled 20 with a high dielectric capacity; 2, to avoid surface leakage and danger of arcing by providing disk-like members of insulating material so situated as to virtually increase the distance between metallic portions to be insulated from each other; 3, to provide certain metallic parts of the structure with sleeves of insulating material independent of the general body of insulating material used as a covering for the strain; 4, to provide the 25 body portion of the strain insulator with a groove whereby it serves as an insulator for supporting an electric conductor disposed at a right angle to the general direction of the axis of the strain insulator; 5, to so shape 30 the metallic parts as to facilitate the assembling of the device complete; 6, to provide an efficient bearing surface of insulating material so disposed that the mechanical stress is distributed throughout a comparatively 35 large area, thereby tending to prevent distortion and also to prevent arcing; 7, to incorporate in the strain insulator a metallic link which is closed upon itself at a point embedded within the insulating material and 40 provided with projecting portions to be engaged by a tension member.

Reference is to be had to the accompanying drawings forming a part of this specification, in which similar characters of reference 50 indicate corresponding parts in all the figures.

Figure 1 is a central vertical section through a strain insulator, made in accordance with my invention, and showing an electric conductor disposed at right angles to the general direction of tension. Fig. 2 is a central

vertical section upon the line 2—2 of Fig. 1, looking in the direction of the arrow, and showing the disposition of the stems 6, sleeves 10 and disk 4, and also showing the 60 manner of mounting a tie wire 25 so as to secure a conductor 24 resting upon the top of the strain insulator; Fig. 3 is a perspective view showing one of the links of the strain insulator, this link being provided with a 65 closed portion which is to be completely embedded within the insulating material, and with a threaded stud projecting from this link; and Fig. 4 is an elevation of the washer of insulation material, and which sustains 70 the mechanical and dielectric stress of the device.

A disk 4 of metal is provided with holes 5 of frusto-conical form and with stems 6, also of frusto-conical form, these stems being intermediate of the holes as indicated in Fig. 3, and joined by a bridge portion 7, the stems, bridge portion and disk thus constituting an endless or closed member. A threaded stem 8 is integral with the bridge portion 7, and 80 projects therefrom. A threaded socket 9 fits revolvably upon the stem, and is provided with an eye 9^a. Fitting into each hole 5 is a sleeve 10 of frusto-conical form and made of insulating material having a comparatively high dielectric constant and a maximum of so-called "crushing" strength. These sleeves 10 are of greater length than the thickness of the disk 4, and when fitted into position each sleeve extends slightly from 90 both ends of the hole in which it is located. Frusto-conical bolts 11, each provided with a threaded cylindrical portion 12, are fitted into the sleeves 10. The threaded portions 12 pass through holes 12^a in a disk 13 of 95 metal. This disk is entirely separate from the disk 4 and has a somewhat different shape. A washer 14^a is provided with holes 14^b. The washer 14^a is made of insulating material having considerable mechanical 100 strength. For this purpose hard rubber, hard fiber or the substance known in the electrical trade as "electrose" may be employed. Nuts 14 threaded internally, are screwed upon the threaded cylindrical portions of stems 12. The disk 13 is provided with a neck 15 which terminates in a socket 16, the latter being provided internally with a thread 17 into which fits an eye-bolt 18 threaded externally for the purpose. 110

The parts just described are assembled as follows: The disk 4 is held in such position

that the screw threaded stem 8 extends upwardly. The sleeves 10 are now placed in the holes 5, and the bolts 11 are next dropped into these sleeves, the threaded portions 12 of these bolts thus projecting considerably from the smaller ends of the sleeve. The washer 14^a is now slipped over the stems 12 and lodged against the disk 4. The disk 13 is now slipped over the stems 12. The nuts 14 are now screwed into position so as to lock the disk 13, washer 14^a and disk 4 firmly together. The entire mechanism is placed in a mold and a quantity of insulating material molded and pressed around and between the parts described so as to form a spheroidal member 19, practically enveloping the several metallic parts. The insulating material 19 is so shaped as to produce disks 20, each preferably of circular form and tapering in thickness toward its outer edge. The member 19 of insulating material is further provided with annular beads 21 separated so as to form a groove 22 for girdling the center of the insulating strain. The structure is now mounted in position, the mechanical stress being upon the eye-bolts 9^a and 18. A conductor 23, such as wire or cable, may now be rested within the grooves 22 intermediate of the annular beads 21. A tie wire 24 is next placed in position so as to secure the conductor 24 in fixed position. The ends 25 of this tie wire are now twisted so as to bend the conductor 24 firmly against the top of the strain insulator.

The closed metallic member made by the bridge 7, the stems 6 and the disk 4 is so disposed within the mass of insulating material 19 as to be completely embedded. In other words, this part of the construction virtually amounts to a strain member having a closed link completely embedded within insulating material. The eye-bolts 9^a, 18 and their connections together perform the office of a turnbuckle. In order that the operation of the turnbuckle may not place the strain member, or any part thereof, in a disadvantageous position, the disks 20 are made circular so that no matter what part of the disk may be upward or downward, the symmetry of the general structure is not disturbed, and its insulating qualities are not affected.

It will be noted that in carrying out the objects above discussed my improved device serves the purpose of an ordinary strain insulator and a turnbuckle, and further performs the office of an insulator for a conductor running in a different direction than the general direction of mechanical strain.

The sleeves 10 because of their peculiar conformity are of great strength, and being frusto-conical in form, they enable the mechanical stress of the bolt 11 to be distributed through the entire thickness of the disk 4, that is to say, a mechanical stress tending to pull the bolts 11 from their fastenings must

cause these bolts to wedge laterally against the sleeves 10 of insulating material, and these sleeves are unable to yield in a lateral direction because of the reinforcing action of the disk 14 encircling them. The great length of the sleeves 10, due to distribution of mechanical strains over comparatively large areas, throws upon the disk 4 a mechanical stress extending practically throughout the entire thickness of the same, and thus tends to prevent the breaking of the bolts 11, and at the same time prevents destruction of the insulating sleeves 10.

It will be understood that, generally speaking, in insulating strains employing bolts or their equivalents, there is ordinarily a great tendency for the bolts to pull in two, especially at points comparatively near their heads. This trouble is avoided by my construction.

While the sleeves may be made of comparatively tough insulating material, such as hard rubber, or fiber, and the body portion 19 may be of less mechanical strength than the sleeves, I do not limit myself to any particular material for insulating purposes. Generally speaking, however, I prefer to employ a high quality of non-conducting material for the sleeves 10, and a cheaper grade of the same for the member 19. Neither do I limit myself to the particular shape or conformity of any of the parts shown, nor to the exact mechanism disclosed.

Having thus described my invention, I claim as new and desire to secure by Letters Patent:

1. A strain insulator, comprising a disk provided with holes of tapering diameter, sleeves of insulating material fitted into said holes, bolts of tapering diameter fitted into said sleeves and extending through said disk, said bolts being separate from each other, mechanism connected with said bolts for exerting thereupon a mechanical strain, and means for connecting said disk to a tension member.

2. A strain insulator, comprising a disk provided with holes of frusto-conical form, sleeves of insulating material mounted within said holes and also of frusto-conical form, bolts provided with portions of frusto-conical form fitted into said sleeves, said bolts being separate from each other, a disk provided with apertures for receiving said bolts, and means for preventing the removal of said bolts from said second-mentioned disk.

3. A strain insulator, comprising a plurality of metallic tension members, separate from each other and disposed side by side, means for insulating said members from each other, and a member of insulating material enveloping said metallic tension members and provided with annular beads, said annular beads extending entirely around said member of insulating material and being sep-

arated so as to form therebetween a groove for holding a conductor, and disks of insulating material integral with said member of insulating material and of much greater diameter than said beads, so as to give to said member of insulating material substantially the form of a spool.

4. The combination of a pair of metallic disks, a member of insulating material separating said disks and insulating the same from each other, each of said metallic disks being provided with holes and further provided with bolts, the bolts of one metallic disk extending into the holes of the other metallic disk and being completely encircled by the same, and a body of insulating material

formed upon the outside of said metallic disks and fashioned at its ends into disks of comparatively large size.

5. The combination of a plurality of metallic members, means for insulating the same from each other, and a body of insulating material enveloping portions of said metallic members, said body of insulating material being provided centrally with a groove.

In testimony whereof I have signed my name to this specification in the presence of two subscribing witnesses.

LOUIS STEINBERGER.
